UNITED STATES PATENT OFFICE.

ROBERT FARREN AND CHARLES T. CLARK, OF CLEVELAND, OHIO.

ELECTRIC RADIATOR-HEATER.

1,121,341.

Specification of Letters Patent. Patented Dec. 15, 1914.

Application filed September 17, 1914. Serial No. 862,251.

To all whom it may concern:

Be it known that we, ROBERT FARREN and CHARLES T. CLARK, citizens of the United States, residing at Cleveland, in the county 5 of Cuyahoga and State of Ohio, have invented certain new and useful Improvements in Electric Radiator-Heaters, of which the following is a specification.

This invention relates to electrically 10 heated radiators, in which local electrical devices are used for heating water in a radiator or the like, and it is characterized by improvements with respect to the construction and arrangement of the heating 15 units with respect to other parts of the radiator in order to effect a circulation of the water and an advantageous location of the heating devices.

The invention is illustrated in the accompanying drawing, which is a side elevation, partly in section, of a radiator provided with the heater.

Referring specifically to the drawings: 1 indicates a radiator of any suitable construction, having vertical tubular or hollow members, and a hollow horizontal base 12 extending across and communicating with the lower ends of the radiator sections. Within this lower cross connection is located a tube 2 which extends through a gland 7 at the end of the radiator. The inner end of this tube opens into the hollow member 12, and the tube is surrounded by another tube 4 which incloses the heating 35 coils 3 located between the tubes 2 and 4 and arranged to heat both of them. A screw plug 13 may be used to close the end of the coil tube 4.

The outer end of the inner tube 2 is connected by an elbow 5 to the lower end of an upright pipe 6 which is connected at its upper end by an elbow 14 to the top cross connection of the radiator sections. This tube 6 is surrounded by a heating coil 10 inclosed 45 in a tube 11. A switch in the box 8 controls the circuit connections 9 to the respective

coils, and is preferably so arranged that either or both of the coils may be used according to the degree of heat required.

The water in the lower cross chamber of 50 the radiator is heated by the coil 3, at both the surface of the pipe 2 and the pipe 4, and the water in the riser 6 is heated by the coil 10. This induces a circulation, the hot water flowing through the tube 2 and up 55 through the tube 6 and returning through the radiator sections to the lower chamber. The coils can be readily removed when desired by loosening the gland 7 and disconnecting the upper elbow 12, without disassembling the radiator sections.

What we claim as new is:

1. A heater comprising a radiator having a lower chamber, a pipe projecting into said chamber, and opening at its inner end, a 65 vertical pipe connected to the outer end of said pipe and to the top of the radiator, and a heating coil surrounding the first mentioned tube, within said lower chamber.

2. A heater comprising a radiator having a lower chamber, an inner tube projecting into said chamber and open at its inner end, an outer tube surrounding said inner tube within said chamber, a heating coil located between the inner and outer tubes, and a 70 pipe connection from the outer end of the inner tube to the upper part of the radiator.

3. A heater comprising a radiator having a lower water chamber, a tube projecting into said chamber, a coil surrounding said tube within said chamber, a pipe connection from the outer end of said tube to the upper part of the radiator, and a heating coil surrounding said tube.

In testimony whereof, we affix our signatures in presence of two witnesses.

ROBERT FARREN.
CHARLES T. CLARK.
